UNITED STATES PATENT OFFICE.

JENNIE WHITNEY, OF OMAHA, NEBRASKA.

CONTINUOUS FASCINE.

No. 825,996.

Specification of Letters Patent.

Patented July 17, 1906.

Application filed October 27, 1905. Serial No. 284,676.

To all whom it may concern:

Be it known that I, JENNIE WHITNEY, a citizen of the United States, residing at Omaha, in the county of Douglas and State 5 of Nebraska, have invented certain new and useful Improvements in Continuous Fascines, of which the following is a specification.

This invention relates to a new and useful continuous fascine.

10 The object of my invention is to provide a comparatively inexpensive continuous fascine so constructed as to overlap the river-bank to prevent the stream from cutting or eating away the same, and, further, to collect 15 all silt, sand, weeds, and all permeable substances that may be in the stream, thus in time forming a solid mass alongside the river-bank.

Referring to the accompanying drawing, 20 forming a part of this specification, and wherein like characters of reference denote similar parts throughout the drawing, the figure discloses a perspective view of my continuous fascine, showing the manner in which it is secured to the river-bank and held in the stream.

In constructing one of my continuous fascines I use a plurality of willow poles or timbers 1, spaced a suitable distance apart and 25 provided with the wire covering or netting A, which overlaps at both ends of the poles or timbers 1, as shown in the drawing at a and b. This structure, it will be observed, forms a mat for the fascine proper, which 35 will be more fully hereinafter described. Suitably secured to these poles or timbers 1 and extending upward therefrom at a suitable angle are the shield members or poles 2, which are braced and strengthened by means 40 of the cross-pieces 3. Secured to the forward or front side of the poles or shield members is the wire covering or netting B, which forms the front side of the brush-compartment D.

45 It will be observed that the wire-netting A, forming the bottom, and the wire-netting B, which forms the front side of my fascine, forms a triangular compartment D on the top of the netting A and near the top thereof, 50 which compartment D is adapted to be filled

with hay, straw, brush, willows, or any other permeable substances that may be gathered on the river-banks, which is adapted to collect all silt, sand, and other solids in the stream, thus in time forming a solid mass 55 which acts as a shield or wall to prevent the current from cutting or eating away the river-bank proper.

It will be observed that my continuous fascine overlaps and lies alongside the river-bank, as shown in the drawing, thus preventing any destruction of the same by high water or logs and in floating down the stream which has heretofore been the great trouble in ripraping construction.

60 My continuous fascine is held and secured in place upon the river-bank by securing the overlapping end a of the wire-netting A by any suitable means to the stakes or pilings 4, which are driven into the earth upon the bank, as shown, and the opposite end b of the covering or netting A is held and weighed down by any suitable means, such as sandbags or the like 6, which are secured to the overlapping end b by means of the cables 5. 75

It is of course understood that my continuous fascine may be made of any suitable wire covering or netting and poles or timbers of any length and size.

Having thus shown what I consider the 80 preferable way of carrying out my invention, what I claim as new, and desire to secure by United States Letters Patent, is—

1. A continuous fascine, comprising a base or mat, a body or wall of permeable substance protected on its lower side by means of said base or mat and on its outer side by means of a wire covering, substantially as shown and described.

2. A continuous fascine, comprising a wire 90 and willow base, or mat, an upright shield or open wall suitably secured to said mat or base, permeable substances adapted to be placed between said shield or wall and wire mat or base to collect silt, sand and other 95 solids in the stream, substantially as shown and described.

3. A continuous fascine, comprising a base or mat composed of a plurality of poles or timbers provided with a suitable wire cover- 100

ing, an upright shield or wall extending from said base or mat, a triangular compartment formed between said mat and upright shield or open wall adapted to be filled with permeable substances for collecting silt, sand and other solids in the stream, substantially as shown and described.

In testimony whereof I affix my signature in presence of two witnesses.

JENNIE WHITNEY.
